UNITED STATES PATENT OFFICE.

JOHN R. BLAKESLEE, JR., OF CLEVELAND, OHIO.

FORGING-MACHINE.

No. 868,321.

Specification of Letters Patent.

Patented Oct. 15, 1907.

Application filed February 23, 1905. Serial No. 246,835.

To all whom it may concern:

Be it known that I, JOHN R. BLAKESLEE, Jr., a citizen of the United States, and a resident of Cleveland, county of Cuyahoga, and State of Ohio, have invented 55
5 a new and useful Improvement in Forging-Machines, of which the following is a specification, the principle of the invention being herein explained and the best mode in which I have contemplated applying that principle, so as to distinguish it from other inventions.

10 My invention relates to upsetting machines for imparting to hot metal various required forms, through the medium of suitable dies and forming tools.

Said invention relates particularly to upsetting or forging machines such as is shown and described in Patent 15 No. 737065 issued to John R. Blakeslee, August 25, 1903, the machine to which my invention is applied being of the same general form as that of said patent.

The object of my invention is to effect a forging or upsetting operation at two ends of the work simultaneously and to effect such operation in an economical and efficient manner.

My invention consists of means hereinafter fully described and particularly set forth in the claims.

The annexed drawings and the following description 25 set forth in detail certain means embodying the invention, such disclosed means constituting but one of various mechanical forms in which the principle of the invention may be used.

In said annexed drawings:—Figure 1 represents a plan 30 of a portion of an upsetting or forging machine such as is shown in the above-named patent, the construction being shown as modified by the introduction of my invention. Fig. 2 represents a partial plan and a partial horizontal section taken upon the planes indicated by 35 the lines 2—2, Fig. 3. Fig. 3 represents a vertical section of a portion of the machine-frame, die-parts and die-slide and a portion of one of the operating links connected with the latter, such section being taken upon the plane indicated by line 3—3 of Fig. 1. Fig. 4 represents a vertical section of the parts shown in Fig. 3 40 taken upon the plane indicated by line 4—4 in said figure. Fig. 5 represents an end view of one of the die-parts, parts connected therewith being shown in vertical section. Fig. 6 represents a perspective view of one 45 of said die-parts. Fig. 7 represents elevational views partly in section of the finished product resulting from the use of the particular dies illustrated.

The dies illustrated and embodied in my invention are particularly adapted for use in connection with the 50 formation of turn-buckle blanks, but the principle of the invention may be applied in any case where it is necessary to perform a forging or upsetting operation upon both ends of the same structure simultaneously.

The general construction and operation of the upsetting machine to which my invention is applied being 55 described in the above-named patent, I shall merely describe those parts directly pertaining to my improvement. As in said patented machine, the machine herein described is provided with a reciprocable header-slide (not shown) and heading-tool A mounted thereon. 60 This header-slide co-operates with a die-slide B whose reciprocatory path is at right angles with respect to the reciprocatory path of the header-slide and heading-tool. In connection with these two elements is employed a two-part die, the one part C of which is mounted adjacent to the vertical bearing surface b formed on the frame B', such surface being, as shown, parallel with the direction of reciprocation of the header-slide and tool, as shown in Fig. 1. The bottom of said die-part C is formed with a tongue c which slides in a groove b' formed in the frame, so that the said die-part is movable toward and from the abutment-plate B² of the machine, the direction of such movement being, as will be readily understood, the same as that of the header-slide. Seated in a bore c' of said die-part is a plunger c² which projects from the front face c³ of the die-part and is actuated to assume the position shown in Fig. 2 by a coil-spring c⁴. The said plunger is provided with a stem c⁵ which projects through the back end of the die-part and is provided with nuts c⁶ which hold the plunger in place, as will be readily understood. The said spring c⁴ is of a strength such as to move the die-part away from the abutment plate to the full extent of the possible projection of the plunger therefrom, when such die-part is free to so move. The inner or working-face 70 c⁷ is provided with an intaglio c⁸ which is of a form such as to intersect the two end faces of the die-part, as shown. The particular form of intaglio shown is adapted to receive a structure which is to be operated upon at both ends to form a turn-buckle blank. 75

Upon that face of the die-slide B opposing the die-part C is formed an under-cut groove b², Figs. 1 and 3, in which groove is slidably mounted a tongue c⁹ of the complementary die-part C'. It will therefore be seen that this die-part is slidable in the same direction as is die-part C, that is, toward and from the abutment-plate B². Said die-plate C' is provided with a plunger c² attached and mounted in a manner exactly similar to that of the plunger of die-part C. Projecting from the inner face of die-part C' are two horizontal rods 100 c¹⁰, c¹⁰, fixed thereto and which project into two guiding bores c¹¹, c¹¹, formed in the opposing die-part C, such rods being adapted to freely slide and snugly fit in said bores. These rods and bores, while they allow the two die-parts to freely approach and recede from 105 each other, fix such parts relatively to each other in

the direction of movement of the reciprocating tool A, and hence preserve the required alignment of the said two die-parts. A groove b^3 is cut in the frame in which slides a guiding tongue b^5 formed in slide B, Fig. 3, whereby the proper movement of said slide is assured. The axis of the tool A lies in a straight line containing the axis of the forming space formed by the two intaglios of the two die-parts, and in this line of axis also lies the axis of the fixed tool B³ which is secured to the 10 abutment-plate B². It will therefore be seen that the two tools may enter the opposite ends of the forming-space of the die, when the die-parts are brought together, as shown in Fig. 2. The two tools A and B³ are respectively provided with shoulders b^4 and a , 15 which determine the extent of maximum entrance of said tools into the die.

When the header-slide and tool A are withdrawn from contact with the die, and the die-slide B is also in its withdrawn position, the plungers c^2 , c^3 , back the 20 two die-parts away from the abutment-plate B², as shown in Fig. 1, and maintain such position until the machine is caused to operate, as hereinbefore described. The properly prepared, heated structure to be operated upon by the tool, is now placed in the intaglio of 25 the die-part C, the heated ends thereof projecting the necessary distance into the end portions of such intaglio. The machine now being started the die-slide B moves toward the die-part C so as to bring the latter and the die-part C into contact, as shown in Fig. 2, 30 thus securely clamping the structure to be operated upon between said two parts. Immediately upon such action the tool A enters the end of the die and strikes the metal of the clamped structure. Upon further forward movement of said tool the entire die is moved 35 forward against the action of plungers c^2 , c^3 the actuating springs c^4 of the latter being compressed. This forward movement is continued until the tool B³ strikes the opposite end of such metal structure. Immediately following such engagement of said tool, the up- 40 setting or forging operation begins and the forward movement of the tool A and die is continued until the tools have entered the die to their full extent, that is, until the shoulders a and b^4 abut the ends of said die, as shown in Fig. 2. Tool A is thereupon withdrawn 45 and is followed by the die, the movement of the latter being effected by the spring actuated plungers. Such action causes the tool B³ to be withdrawn and upon the continuation of the retracting movement of tool A the die resumes its normal position, in which the tools A 50 and B³ are completely withdrawn therefrom.

Other modes of applying the principle of my invention may be employed instead of the one explained, change being made as regards the mechanism herein disclosed, provided the means stated by any one of 55 the following claims or the equivalent of such stated means be employed.

I therefore particularly point out and distinctly claim as my invention:

1. In upsetting mechanism, the combination of a die- 60 part fixed in one and movable in another direction; a complementary die-part movable in both said directions, means normally positioning said die-parts in their common direction of movement; a heading-tool movable in such common direction and adapted to cooperate with said die-parts;

and a fixed heading tool also adapted to cooperate there- 65 with.

2. In upsetting mechanism, the combination of a fixed abutment; a die-part movable transversely of said abutment; another and complementary die-part movable both transversely of and parallel with said abutment; resilient 70 means normally positioning said die-parts in their common direction of movement; a heading-tool movable in such common direction and adapted to cooperate with said die-parts; and a fixed heading-tool mounted in said abutment and likewise adapted to cooperate with said die-parts. 75

3. In upsetting mechanism, the combination of one die-part fixed in one and movable in another direction; a complementary die-part movable in both said directions; a movable heading-tool and a fixed heading tool both cooperating with said die-parts; spring-actuated means normally projecting from said die-parts and mounted so as to be capable of yielding; and a fixed abutment with which said means contact. 80

4. In upsetting mechanism, the combination of two slides 85 angularly related to one another; a die-part mounted in one of said ways; a die-slide mounted in the other of said ways; a second die-part mounted upon said slide and movable in the direction of movement of said first-named die-part; and a reciprocable heading-tool and a fixed heading-tool cooperating with said die-parts. 90

5. In upsetting mechanism, the combination of a reciprocable member including a heading-tool, a second heading-tool fixedly mounted, a two-part die cooperating with said tools, and movable toward and from said second tool, one of the parts of said die being movable in a direction 95 transverse relatively to the direction of movement of said member, mechanism for so moving said part, said member arranged to move said die toward said fixed tool, and means for retracting such die upon the withdrawal of said member. 100

6. In upsetting mechanism, the combination of a fixed abutment; a die-part movable transversely of said abutment; another and complementary die-part movable both transversely of and parallel with said abutment; spring-actuated plungers borne by said die-parts respectively and adapted to cooperate with said abutment to normally position said die-parts in their common direction of movement; a heading-tool movable in such common direction and adapted to cooperate with said die-parts; and a fixed heading-tool mounted in said abutment and likewise adapted to cooperate with said die-parts. 110

7. In upsetting mechanism, the combination of a reciprocable member including a heading-tool; a die-slide reciprocable in a direction transverse relatively to the direction of movement of said member; a die-part slidable in the 115 direction of reciprocation of said tool; a complementary die-part mounted upon said slide and slidable in the direction of movement of said member; a fixed abutment; a second heading-tool mounted upon the latter, said die-parts cooperating with said heading-tools, said reciprocable member arranged to effect movement of said die-parts toward said abutment; and retracting means connected with said die-parts and arranged to normally hold the same a given distance from said abutment. 120

8. In upsetting mechanism, the combination of a reciprocable member including a heading-tool; a die-slide reciprocable in a direction transverse relatively to the direction of movement of said member; a die-part slidable in the direction of reciprocation of said tool; a complementary die-part mounted upon said slide and slidable in the 130 direction of movement of said member; a fixed abutment; a second heading tool mounted upon said abutment, said die-parts being adapted to cooperate with said heading-tools, and said reciprocable member being adapted to effect movement of said die-parts towards said abutment; and spring-actuated plungers borne by said die-parts and adapted to normally hold the same a given distance from said abutment. 135

9. In upsetting mechanism, the combination of a fixed abutment; a die-part movable transversely of said abutment; another die-part movable both transversely of and parallel with said abutment; means slidably joining said 140

die-parts in the individual direction of movement of said second die-part; means normally positioning said die-parts in their common direction of movement; and a heading-tool movable in such common direction and adapted to cooperate with said die-parts.

- 5 10. In upsetting mechanism, the combination of a fixed abutment; a die-part movable transversely of said abutment; another die-part movable both transversely of and parallel with said abutment; guide-rods mounted in one of said die-parts and slidably engaging the other thereof; said guide-rods being disposed parallel with said abutment; spring-actuated plungers borne by said die-parts respec-

tively and adapted to cooperate with said abutment to normally position said die-parts in their common direction of movement; a heading-tool movable in such common 15 direction and adapted to cooperate with said die-parts; and a fixed heading-tool mounted in said abutment and likewise adapted to cooperate with said die-parts.

Signed by me, this 20th day of Feb'y 1905.
